UNITED STATES PATENT OFFICE.

FREDERICK G. SIMPSON, OF SEATTLE, WASHINGTON.

RADIO TELEGRAPH AND TELEPHONE SYSTEM.

1,217,517.

Specification of Letters Patent. Patented Feb. 27, 1917.

Application filed May 25, 1916. Serial No. 99,914.

To all whom it may concern:

Be it known that I, FREDERICK G. SIMPSON, citizen of the United States, residing at Seattle, in the county of King and State of Washington, have invented a certain new and useful Improvement in Radio Telegraph and Telephone Systems, of which the following is a specification.

My invention relates to improvements in radio telegraph and telephone systems, but more particularly to the transmitting apparatus thereof, and the object of my invention is to provide a novel combination of well known elements to form a transmitting system which shall include as principal parts thereof, the elevated conductors of an antenna, a condenser and a spark-gap, for radio transmission of energy in the form of electromagnetic waves whereby, in the operation of such system the spark discharge across said spark-gap, due to a charge of electricity in different parts of said transmitting system, but principally in said condenser, will be instantly quenched upon the first discharge of said condenser, such discharge consisting of a uni-directional impulse of electric current, following which no spark would occur in said spark-gap in response to resultant oscillations of the same charge in the associated antenna circuit.

I accomplish this object by circuits and well known forms of instruments when arranged in accordance with any one of the several plans that are diagrammatically illustrated in Figures 1, 2 and 3, respectively, of the accompanying drawings, each of which plans embodies my invention; but in each of said Figs. 1, 2 and 3 my said invention is shown in a slightly different form.

Referring to the drawings, in each of the Figs. 1, 2 and 3 the numeral 5 designates the elevated conductors of an antenna of a radio telegraph or telephone system with which is associated an inductance coil, as inductance coils 11 or 19, an adjustable condenser 6, an earth connection 7, an adjustable spark-gap 8 and terminals 9 and 10, of a key-controlled charging circuit.

Referring particularly to Fig. 1, the elevated conductors 5 of the antenna are connected to one terminal of the condenser 6 through the inductance coil 11, the other terminal of said condenser 6 being connected by conductor 12 to the earth 7.

At a point between the inductance coil 11 and the adjacent terminal of the condenser

6 is connected one terminal 9 of a key-controlled charging circuit while the other terminal 10 of said charging circuit is connected to the conductor 12 at a point adjacent to the other terminal of said condenser 6.

One terminal of the spark-gap 8 is directly connected by a conductor 13 to the earth 7 while the other terminal of said spark-gap 8 is connected to one end of a conductor 14 whose other end is connected to the inductance coil 11, said other end of said conductor 14 being adapted in a well known manner to be adjustable to connect it to said inductance coil 11 at any one of different points thereon as may be required under different conditions of operation.

In said Fig. 1, contemplating the elevated conductors 5 of the antenna, the inductance coil 11, the condenser 6, the conductor 12 and the earth 7 as constituting an oscillator energized by a charging circuit connected with terminals 9 and 10; then the potential distribution and the wave lengths of oscillations in such oscillator will be governed largely by the relative capacities of the elevated conductors 5 of the antenna with respect to the earth 7 and the condenser 6, and the amount of inductance produced by the coil 11; and hence the wave lengths of oscillations in said oscillator and the position therein of the nodes of potential during such oscillations, will also be governed thereby.

Now, if it be assumed that the curved broken lines 15 in said Fig. 1 represents the potential distribution in said oscillator and the nodes of potential as fixed therein at points where one of said broken lines 15 intersects the inductance coil 11 and where the other of said broken lines touches the earth 7; then, since the terminals of the spark-gap 8 are connected at said points to said oscillator by wires 14 and 13 respectively, it is obvious that when the condenser 6 is charged to a degree to cause a spark discharge across the spark-gap 8 (thus to discharge said condenser 6), then such spark will be instantly quenched upon the termination of said discharge in spite of resultant oscillations in said oscillator, since there can be no difference in potential between the terminals of said spark-gap 8 by reason of it being connected to said oscillator at nodal points of potential.

More fully, the capacity of the condenser 6 and the point of connection between the conductor 14 and the inductance coil 11 may

be changed to suit antennæ of different capacities and the spark-gap 8 may be adjusted to suit different conditions of operation.

The arrangement of parts of my invention 5 as shown in Fig. 2 is like their arrangement shown in Fig. 1 in mode of operation and in all particulars except that in the plan of Fig. 2 I have provided an inductance coil 16 connected to extend between the ground 10 10 7 and the point where the terminal 10 connects with one terminal of condenser 6.

The arrangement of parts of my invention 15 as shown in Fig. 3 is like their arrangement shown in Fig. 1 in mode of operation and in all particulars except that in place of the 20 inductance coil 11 of Fig. 1 I have substituted an inductance coil 19 to which is adjustably connected one end of a conductor 20 whose other end is connected to the elevated conductors 5 of the antenna, whereby the node of potential in the oscillator may be caused to be located at the required point by adjusting the capacity of the condenser 6 with relation to the capacity of the elevated 25 conductors 5 of the antenna with respect to the earth 7, and changing the position of the point of contact between the conductor 20 and the inductive resistance 19.

Manifestly, under some conditions of operation an adjustable condenser 6 may be replaced by a condenser of a fixed capacity, in which case, changes in the position of the nodes of potential in the oscillator would be effected by making changes in the amount of 30 inductance contained therein; and also a non-adjustable spark-gap might be substituted for the spark-gap 8, in which case suitable changes might be made in the energy supplied by the charging circuit and in the 35 capacity of the condenser 6 to compensate for lack of adjustment of such substituted spark-gap.

It is plain that many changes may be made 40 in the arrangement of a circuit or associated 45 circuits, including an antenna, to form a transmitting system of energy in the form of electromagnetic waves; to which transmitting system, energy, in the form of an electric current, is communicated from its 50 source and is accumulated therein in static, or potential form. That in all such arrangements of the circuit, or circuits, of such transmitting system there may be included a spark-gap, the terminals of which are connected to points in said transmitting system 55 which will permit the static or potential energy resident therein to discharge across

said spark-gap in the form of a uni-directional electric current impulse thereby producing an oscillating circuit within said transmitting system and that said points of connection of the terminals of said spark-gap shall be at nodes of potential within said transmitting system so that no potential difference shall exist between the electrodes 60 of said spark-gap during the existence of such oscillating current.

I do not limit myself to any particular circuit or arrangement of circuits, nor do I limit myself to an exact adjustment of the 70 terminals of the spark-gap with respect to the exact nodes of potential within a radio transmitting system.

It is sufficient for all practical purposes 75 that the terminals of the spark-gap shall be connected to points in said transmitting system which are substantially nodal points of potential distribution during the existence of an oscillating electric current therein.

It is necessary, however, that the point of 80 connection of the terminals of the spark-gap to the oscillating circuit, or circuits, of such transmitting system shall be sufficiently near to nodal points of potential distribution as will limit the difference of electric potential 85 between the electrodes of said spark-gap to an amount insufficient to cause a breaking down of the resistance of said spark-gap; which breaking down of resistance would permit oscillating current to pass through 90 such spark-gap.

What I claim is:

1. In transmitting apparatus of an electrical system of radio communication, the combination with an oscillating circuit which 95 includes an earth connection, an antenna, an inductance and a condenser; of a charging circuit, and a spark-gap whose terminals are connected with said oscillating circuit at nodal points of potential therein. 100

2. A radio system of communication having electric circuits which include an oscillating circuit and a spark-gap whose terminals are connected with said oscillating circuit at points near the nodal points of potential therein, whereby oscillating currents in said oscillating circuit shall have little tendency to jump across said spark-gap. 105

In witness whereof, I hereunto subscribe my name this 12th day of May A. D., 1916. 110

FREDERICK G. SIMPSON.

Witnesses:

FRANK WARREN,

O. JOHNSON.
